UNITED STATES PATENT OFFICE.

CONSTANTINE B. VOYNOW, OF PHILADELPHIA, PENNSYLVANIA.

APPARATUS FOR CLAMPING AND HOLDING RAILS, &c.

SPECIFICATION forming part of Letters Patent No. 629,053, dated July 18, 1899.

Application filed March 24, 1899. Serial No. 710,295. (No model.)

To all whom it may concern:

Be it known that I, CONSTANTINE B. VOYNOW, a citizen of the United States, residing at the city of Philadelphia, in the county of Philadelphia and State of Pennsylvania, have invented certain new and useful Improvements in Apparatus for Clamping and Holding Rails or Parts Thereof During the Formation of Railway-Crossings or the Like, of which the following is a specification.

My invention has relation to an apparatus whereby the rail parts of a crossing may be assembled together at required angles and gages and clamped in required position during the formation of said rail parts into a railway-crossing or the like; and in such connection it relates more particularly to the construction and arrangement of such an apparatus.

Heretofore in the formation of railway-crossings it has been necessary to form for each crossing desired a separate flask or mold, and while the rail parts were in the mold there was nothing to support the parts during the operation of casting except the clay or sand forming the mold or flask. Again, where various degrees of angularity of crossing were required each different angle had to be duplicated in the mold and the rail parts arranged with great care and much labor to correspond to the angle and without any assurance of the maintenance of such angle.

The principal objects of my present invention are, first, to provide an apparatus whereby the rail parts may be quickly assembled into required position and therein held until their meeting parts are cast together without the use of a pattern or mold; second, to provide in such an apparatus means whereby the rail parts may be adjusted with respect to the angle they are required to make with each other, and, third, to provide in such an apparatus means whereby said apparatus may be used for crossings irrespective of the gage of the road or distance between the parallel rails of each track.

My invention, stated in general terms, consists of an apparatus for holding and clamping rail parts in the formation of crossings or the like when constructed and arranged in substantially the manner hereinafter described and claimed.

The nature and scope of my invention will be more fully understood from the following description, taken in connection with the accompanying drawings, forming part hereof, in which—

Figure 1 is a top or plan view of an apparatus embodying main features of my invention, certain of the rail parts and portions of the apparatus being removed. Fig. 2 is a front elevational view of Fig. 1. Fig. 3 is a top or plan view, enlarged, of the central portion of the apparatus, showing the rail parts supported by and clamped in the apparatus. Fig. 4 is a perspective view of a railway-crossing complete. Fig. 5 is a cross-sectional view, enlarged, on the line $x-x$ of Fig. 1. Figs. 6 and 7 are cross-sectional views, still further enlarged, illustrating, respectively, the means for clamping the rail parts in the upper and lower frames of the apparatus. Fig. 8 is an enlarged perspective view of an intersecting portion of the crossing, together with the molds for receiving the molten metal adapted to weld the rail parts together; and Fig. 9 is a cross-sectional view taken on the line $9-9$ of Fig. 8.

Referring to the drawings, the apparatus consists of two frames a and b , the construction and arrangement of each of which are precisely the same, except that one frame b rests above the other frame a . The frame a consists of two parallel girders or beams a' , of inverted-U shape and resting with their flanges a^2 upon a suitable support a^3 . The tops or crowns a^4 of these girders a' serve as the supports for the girders or beams b' , the flanges b^2 whereof, with their supporting-plate, rest upon the said crowns a^4 . The crowns a^4 of the girders a' also serve as supports for the blocks d , which extend along the girders a' to the points at which the girders b' intersect or cross the girders a' . These blocks d are adapted to slide in grooves arranged longitudinally in the crown a^4 of each girder a' , as illustrated in Figs. 5 and 6, and the top d^1 of each block d is provided with a projection d^2 , corresponding to the depression e' in the head e of a rail part e^2 to thus form a firm support for the said rail part. The girders a' are held in a position of parallelism by means of plates a^5 and a^6 , of which a^5 projects from the sides of the girders a' at or near their ends, while

the other plate a^6 projects from the sides at the central point of the apparatus. The plates a^5 and a^6 of one girder a' slide in the corresponding plates a^5 and a^6 of the other girder a' in such a manner that the girders may be shifted inward toward each other or outward away from each other to adapt, when desired, the apparatus for use in the formation of crossings for different gages of track.

10 When shifted, however, to the proper gage, the slide plates a^5 and a^6 are clamped together, for instance, by means of bolts a^7 . The plate a^6 of one of the girders a' is provided with a bracket a^8 , surrounding a central boss a^9 , projecting upward from the bed a^3 of the apparatus. The cross-girders b' are provided in a similar manner with the end slide-plates b^5 and central slide-plates b^6 , which are clamped together by bolts b^7 , and

15 the plate b^6 of one girder b' is provided with a bracket b^8 , swinging on the central boss a^9 . The crown of each cross-girder b' is adapted to support the bearing-blocks f , which correspond in detail to the bearing-blocks d of the girders a' , with the exception that they are not so high, being only sufficient in height to bring their projections f^2 and tops f' into the same horizontal plane as are the projections d^2 and tops d' of the blocks d . The respective heights of the two blocks d and f are illustrated in Figs. 6 and 7. The two sets of girders a' and b' having been adjusted to required gage as explained with relation to girders a' , the angle which the crossing girder b' must make with regard to the base-girders a' may be changed so as to permit the rail parts to be assembled in the formation of a crossing of required angularity in the following manner: To the outer flanges a^2 of the girders a' are secured the ends of two curved tracks g , and upon each of these curved tracks g is adapted to be guided a bracket g' , projecting from one of each set of end sliding-plates b^5 of the girders b' . The two girders b' are turned together about the boss a^9 , the central slide-plates b^6 forming the pivotal connection between the girders b' and said boss, until the desired angle of crossing is reached, when the brackets g' are clamped together to

20 the curved rails g by means of set-screws g^2 or in any other preferred manner.

The frames a and b having been adjusted to required gage and to required angularity, the rail parts e^2 are now inserted and held as follows: The parts e^2 are placed with the head e downward, so that the depression e' in said head rests on the projections d^2 and f^2 of the blocks d and f . Over the flat base e^3 of the rail parts e^2 is now placed a series

25 of yokes k , through which yokes pass the bolts k' , having hook-shaped ends k^2 engaging openings on the sides of either of the two sets of girders. By advancing the nuts k^3 on the bolts k' the yokes k tightly clamp the rail parts e^2 down upon the blocks d and f .

30 To clamp all the parts of the apparatus together—that is, the frames a and b and the

interposed rail parts e^2 —a similar yoke m , bearing upon the rail parts at their ends, is used, as illustrated in Fig. 7. In this instance the bolts k' of the yoke k , which engages in the sides of the lower girders a' , are extended beyond the yoke k and engage the yoke m , which bears upon the base e^3 of the end of the rail parts supported upon the upper girders b' . The ends of the rail parts e^2 which meet at the crossing-points are illustrated as being cut away or beveled so as to leave an opening p and which, as shown, is of oblong shape; but it is to be understood that said openings may be dispensed with, and likewise the steel blocks, without departing from the spirit of my invention. In these openings a steel block p' (see Fig. 4) is adapted to be welded. To weld the rail parts and the inclosed steel block p' together a mold s is formed around the intersecting points, as illustrated in Figs. 8 and 9. This mold s may consist of green sand, a baked-clay core, or a pattern made of cast-iron and is provided with an opening s' , through which the molten metal is poured to form the locking parts r . Inasmuch as the intersecting rail parts do not closely abut, crevices or channels are left for the metal to run into the corners and angles of the intersections, and thus closely to bind or weld the rail parts and block together. The respective locking parts r are also preferably united together in the following manner: In the web e^2 of each intersecting rail part a hole or opening is punched or otherwise formed to permit the molten metal to run through and form a connecting arm or bolt r' , as illustrated in Fig. 9.

Having thus described the nature and objects of my invention, what I claim as new, and desire to secure by Letters Patent, is—

1. In an apparatus for forming railway-crossings, two superposed frames, each consisting of two parallel girders or beams upon which the rail parts are adapted to be supported, said frames being pivotally connected so that they are adapted to cross each other at the required angle of the railway-crossing, substantially as and for the purposes described.

2. In an apparatus for forming railway-crossings, two superposed frames each consisting of two parallel girders or beams, upon which the rail parts are adapted to be supported, the girders of each frame being adjustable with respect to each other so that the distance between the girders of each frame may be varied, substantially as and for the purposes described.

3. In an apparatus of the character described, two frames each composed of parallel girders, one frame being arranged above the other and both frames constituting the support for the crossing rail parts, in combination with blocks arranged on the girders of each frame and adapted to support the rail parts in the same horizontal plane, and means for clamping the rail parts down upon

the blocks, substantially as and for the purposes described.

4. In an apparatus of the character described, two superposed frames crossing each other at the required angle, and means for supporting the rail parts above each frame so that the heads of said rail parts lie in the same horizontal plane, substantially as and for the purposes described.
- 10 5. In an apparatus of the character described, two frames each consisting of two parallel girders adapted to receive and support the crossing rail parts, said frames being superposed, and means for turning one of said frames upon the other so that the frames may cross at a required angle, substantially as and for the purposes described.
- 15

6. In an apparatus of the character described, two sets of superposed parallel girders, each set adapted to receive and support a respective set of crossing rail parts, means for clamping each set of rail parts directly down upon their respective supporting-girders, and independent means for clamping both sets of girders together, substantially as and for the purposes described.

In testimony whereof I have hereunto set my signature in the presence of two subscribing witnesses.

CONSTANTINE B. VOYNOW.
